Specification for Design.

Patented Feb. 16, 1915.

Application filed April 6, 1914. Serial No. 830,072. Term of patent 7 years.

To all whom it may concern:

Be it known that we, GEORGE M. BEARDSLEE and IRA L. FRENCH, citizens of the United States, residing at Chicago, in the county of Cook and State of Illinois, have invented a new, original, and ornamental Design for Lighting-Fixtures, of which the following is a specification, reference being had to the accompanying drawing, forming part thereof, the design being more particularly shown applied to the part of a lighting-fixture which may be employed either as an ornamental scroll, as a chain-link, a bottom or terminal ornament, or as a band or ring ornament for a plate or body shell.

In the drawing: Figure 1 is a side elevation illustrating our new design applied, as indicated by the dotted lines, to a bottom or

terminal ornament for lighting fixtures. Fig. 2 is a side elevation, showing our new design, as applied to an ornamental scroll of a lighting fixture. Fig. 3 is a side elevation, showing our new design applied to a chain link for use in connection with a lighting fixture. Fig. 4 illustrates our new design in perspective. Fig. 5 is a side or edge view thereof. Fig. 6 is a sectional view taken on the line A—A of Fig. 5.

We claim:—

The ornamental design for a lighting fixture, as shown.

GEORGE M. BEARDSLEE.
IRA L. FRENCH.
